R. L. WILCOX

DIE SEPARATING MEANS

Filed Oct. 31, 1921

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE-SEPARATING MEANS.

Application filed October 31, 1921. Serial No. 511,803.

To all whom it may concern:

Be it known that I, RICHARD LESTER Wilcox, a citizen of the United States, residing at Waterbury, in the county of New Haven and State of Connecticut, have invented certain new and useful Improvements in Die-Separating Means, of which the following is a specification, reference being had therein to the accompanying drawings.

10 My invention relates to die separating means, its principal object being to provide simple mechanism for separating the dies of an open die header or upsetting machine.

15 Among other aims and objects of my invention may be recited the provision of a device of the character mentioned with a view to compactness and in which the number of parts are few, the construction simple, the cost of production small, and efficiency 20 of operation high.

The improvements in the details and arrangement of parts will be apparent from an inspection of the accompanying drawings, in connection with the description herein- 25 after contained, and wherein an embodiment of the invention is disclosed for the purpose of imparting a full understanding of the same.

Having more particular reference to the 30 drawings and in connection with which like reference characters refer to corresponding parts in the several figures;

Figure 1 is a front view of a pair of dies of a heading machine or the like and a 35 fragmentary portion of its supporting mechanism with my improved separating means connected therewith;

Figure 2 is a sectional elevation thereof taken generally upon line 2--2 of Figure 1;

40 Figure 3 is a perspective view of one of the dies;

Figure 4 is a modified form of my invention;

Figure 5 is a fragmentary detail of such 45 modified form;

Figure 6 is an alternative form of cam plate; and

Figure 7 is a front view of a pair of dies, similar to Figure 1, with the separating 50 means applied to the underside of the dies.

It has heretofore been the practice to

separate the dies of an open die header or upsetting machine at the wire feed line by parting pins, separating pins or the like, an illustration of such means being shown 55 in Letters Patent No. 1,104,090, dated July 21, 1914, particularly in Figure 4 thereof, and also in Letters Patent No. 1,108,958, dated September 1, 1914, a heavy flat spring, not shown in either of the above patents, 60 bearing upon the upper end of each of the parting pins or separating pins, which move in a path at substantially a right angle to the movement of the dies. With such mechanism the die cap or other part or parts 65 that support the pins must be machined with great care and exactness and each must be in correct alignment with each other and the groove formed by the annular corner faces of the dies, when the dies are in proximity 70 to the wire feed line. If the pins are not so arranged, the lower pointed end thereof will not register with said groove, thus having a tendency to cramp the dies and apply an unequal pressure thereto at different points 75 throughout their length. If this occurs, the dies may be separated more at one end than at the other, and if perchance the minimum separation is at the inner end of the dies a defective feed of the wire results and the end 80 of the wire may abut against the dies and stop the feed.

With the use of such pins the spring pressure upon the end thereof is constant, therefore it requires not only a pressure sufficient 85 to move the dies and cut off the wire but also to resist the pressure of the pin actuating springs, which pressure is constant upon the top of one of the dies during its entire movement. There is no use for this pressure except when the dies are to be separated at the wire feed line, hence more power is necessarily required to actuate the dies. While more powerful mechanism is required to move the dies from the wire feed line to 90 the upsetting line, the dies are usually returned by spring pressure, the strength of which must of necessity also be increased to overcome the needless drag and pressure of the pins.

As the pins are of substantial length the element in which they are mounted must of

necessity be of substantial height to provide proper support therefor and this height, as well as the pin operating springs, requires space that can otherwise be advantageously utilized.

All of the above and other objections of the heretofore conventional method for separating the dies are obviated in my improved device, which occupies the minimum amount of not otherwise required space, pressure is applied only when the dies are to be separated, the necessity of fine machining of the parts is entirely eliminated, and in these, and many other ways, produces results that are advantageous and insure certainty and efficiency in operation, and with mechanism that is of comparatively simple design.

Having more particular reference to the drawings, the numerals 10 and 11 represent the dies, which are of the usual form but having notches 17 at their corners with end walls 16, the base of each of the notches being at an angle to the face of the die. These notches unite to form a V shaped groove substantially as shown in Figures 1 and 7, wherein the dies are near the wire feed line, this being coincident with the line 2—2 of Figure 1. A piece of wire designated 13 is shown in section at this point.

The bed plate upon which the dies are supported is designated 14, and the cap or cover over the top thereof 15.

All of the mechanism above described except the notches 17 in the dies, is of a well known form and operates in an equally well known manner and therefore needs no further description herein.

The means for actuating the dies is not shown herein for the above reason, but the same travel between the wire feed line and the upsetting line, which latter line is designated α — α in Figure 1. From the wire feed line to the upsetting line the dies are positively actuated by relatively powerful mechanism to cut off a piece of the wire rod but are usually returned from the upsetting line by spring mechanism.

In dies of the conventional form designated 10^a in Figure 4, the angular faces 12 extend throughout the length of the die and the cam plate 18^c is provided with notches 21^a having cam faces 19^c upon the bottom thereof.

In the cover 15 is a cam plate 18, preferably dove-tailed therein and having a cam face 19 thereon which inclines from the direction of the upsetting line toward the wire feed line. The use of this cam plate as shown, is not necessary to the successful operation of the machine, nor the means for mounting the same in the cover, because the cam face may be formed upon the cover itself or may be mounted in any other convenient manner.

Another form of cam plate 18^b is shown

in Figure 6, wherein the cam face 19^b is shorter in width than the cam plate, a substantially straight portion 22 leading therefrom. When this form of cam is used it is so arranged that the cam face 19^b is in line 70 with the wire feed line.

In each of the notches 17 is a ball or roller 20 which is held against endwise movement by the walls 16.

In operation the balls or rollers 20 travel 75 with the dies until the latter are near and at the wire feed line, when they are in engagement with the cam face 19 and the angular faces at the base of the notches 17. As the dies move from the wire feed line to the upsetting line, the balls or rollers travel with the dies and away from the cam face 19 so that when in the upsetting line they are in substantially the position shown by broken lines in Figure 1. When the dies are returned 85 to the wire feed line the upper surface of the balls or rollers again contacts with the cam face 19 and moves downwardly, thus separating the dies. Thus my improved die separating mechanism requires a minimum amount of space, pressure is only applied when required, that is, when the dies are at or near the wire feed line, and in these and other ways, the objections to the mechanisms heretofore commonly utilized for separating 95 the dies are eliminated and many obvious advantages secured.

I have shown in Figures 1, 2 and 4 my improved mechanism as applied to the top side 100 of the dies but obviously it will operate equally as well if applied to the underside thereof as shown in Figure 7, or if desired, it may be used upon both top and bottom. If used upon the bottom the balls or rollers 105 20 will ride upon the cam face 19^a of the cam plate 18^a instead of in the V groove as when used upon the top thereof.

In Figure 6 is illustrated another form of cam plate 18^b having notches 21 therein, the bottom of each of the notches having a cam face 19^b connecting with a straight portion 22. The cams 18^b and 18^c as illustrated in Figures 4, 5 and 6, may be used with the form of dies shown in Figures 1, 2, 3 and 7, 110 if desired, in which case the rollers 20 will project into both the notches in the cam plate and those in the die.

There are minor changes and alterations that can be made within my invention, aside 115 from those herein suggested, and I would therefore have it understood that I do not limit myself to the exact construction herein shown and described, but claim all that falls fairly within the spirit and scope of the appended claims.

Having described my invention what I claim as new and desire to secure by Letters Patent, is:

1. In combination with the dies of a heading machine or the like; of means for sepa-

rating the dies, wherein the dies are each provided with one or more notches in the corners thereof, comprising one or more circular elements in each of the notches and 5 movable with the dies, and a cam with which the circular elements engage when near the wire feed line.

2. A die for a heading machine or the like, having one or more independent notches 10 in the corners thereof between the ends of the die, the bases of the notches being at an

angle to the faces of the die forming each of said corners.

3. A die for a heading machine or the like, having square corners and one or more 15 separate notches in said corners between the ends of the die, the bases of the notches being at an angle to the faces of the die forming each of said corners.

In testimony whereof, I have hereunto 20 affixed my signature.

RICHARD LESTER WILCOX.
